UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING UPON BOOTS OR SHOES.

1,273,324.

Specification of Letters Patent. Patented July 23, 1918.

Application filed June 10, 1914. Serial No. 844,209.

To all whom it may concern:

Be it known that I, MATTHIAS BROCK, a citizen of the United States, residing at Boston, in the county of Suffolk and State 5 of Massachusetts, have invented certain Improvements in Machines for Operating Upon Boots or Shoes, of which the following description, in connection with the accompanying drawings, is a specification, like reference characters on the drawings indicating like parts in the several figures.

This invention relates to machines for operating upon boots or shoes, and particularly to machines for stretching boots or 15 shoes, preferably as an intermediate step in the manufacture thereof.

A general object of the invention is to provide an improved stretching machine of general utility in the art of shoe making and 20 shoe fitting, and particularly to provide a stretching machine which can be operated rapidly and safely by comparatively unskilled operators. In the following detailed description of the invention particular reference is made to its utility in performing an important step in a new process of making shoes which is the subject matter of a 25 copending application, Serial No. 103,647 filed June 14, 1916. It will be understood, 30 however, that the invention is not restricted to a machine for use in the practice of a particular process of making shoes and, moreover, it is obvious that the illustrated embodiment of the invention is also not restricted in its utility, but can be used generally in the manufacture of shoes, whether 35 such shoes be made by the stitchdown process, the turn shoe process or by any of the well-known processes of making shoes.

40 In the manufacture of shoes by a former process disclosed in U. S. Letters Patent to Karl Engel, No. 931851, granted August 24, 1909, the toe and heel ends of the shoe upper are molded to the shapes of the corresponding parts of a last and an insole is 45 stitched to said upper before said upper is placed upon the last. To insure the production of a properly fitted shoe by this process, it is substantially essential that the 50 upper should be cut very carefully to pattern, and that the insole should be stitched carefully to the molded upper. When this is done, difficulty is experienced in inserting

the last, particularly in the manufacture of the larger sizes of shoes; and, moreover, the mere insertion of a last of the proper size 55 in a shoe thus made does not effect such proper stretching of the upper in all directions as is essential to the production of a finished shoe having a neat and smooth appearance. 60

An important object of the present invention, therefore, is to facilitate the carrying out of the above-mentioned new process of making shoes involving the general principles of operation of the process disclosed 65 in the Letters Patent above identified, said new process comprising, as a further important step, a stretching of the upper, preferably in various directions and along 70 different dimensions, whereby those parts of the upper which are not shaped by the toe and heel molding operations may be properly stretched as an intermediate step between the molding and insole securing operations, on the one hand, and the insertion 75 of the last upon which the shoe is supported for the finishing operations on the other hand.

Another important object of the invention 80 is to provide a machine which will not only stretch a shoe produced by the initial steps of the process above referred to, to improve the fit and general appearance of said shoe, but will also stretch a shoe thus 85 produced to increase its size, whereby a material saving in stock may be effected.

Important features of the invention reside in the fact that in stretching each shoe a uniform predetermined amount, the stretching means being initially adjustable to a variable point having a fixed relation to the size of the shoe to be stretched before the actuation of the stretching means, and suitable means being provided for guiding the operator in making such initial adjustment of the mechanism. 90

In accordance with other features of the invention, the shoe stretching is effected by power driven mechanism, the operation of 100 which mechanism is automatically controlled. The illustrated machine is especially organized so that there will be little danger of over-stretching the shoe and tearing or otherwise injuring it. 105

Other important features of the invention

are the provision of means for confining the heel of the upper upon the heel shaped form while the forepart of the upper is being operated upon by the forepart stretching means, the provision of means for shaping the heel seat during the stretching operation, and the provision of means for initially adjusting the stretching form to fill the upper before the operation of the mechanism by which the stretching form is expanded.

Other objects and important features of the invention will appear from the following description and claims when considered in connection with the accompanying drawings.

In the accompanying drawings,

Figure 1 is a side elevation of a machine embodying the invention;

20 Fig. 2 is a rear elevation;

Fig. 3 is a perspective view of one of the stretching mechanisms with parts broken away to show parts otherwise hidden from view;

25 Fig. 4 is a perspective view of one of the expanding forms;

Fig. 5 is a longitudinal section of one of the expanding forms in contracted condition;

30 Fig. 6 is a section similar to Fig. 5, but in expanded condition;

Fig. 7 is a perspective view of the shoe before stretching; and

35 Fig. 8 is a perspective view of the shoe shown in Fig. 7 after stretching.

The illustrated machine is preferably provided with two pairs of stretching mechanisms in order that one pair of shoes may be allowed to set to its stretched condition

40 while another pair of shoes is being placed upon the forms by the operator. Moreover the two mechanisms are preferably constructed to operate upon different ranges of sizes of shoes whereby the total size range 45 of the machine is considerable. The stretching mechanisms of each pair are preferably operated simultaneously.

After the shoe has been located upon the form, in order that the shoe may not be torn during the stretching, the operation of the machine is comparatively slow, the driving means comprising a main driving shaft 2 mounted in bearings in the frame 3 and driven by connections from a power shaft to 55 the pulley 5. From the driving shaft motion is transmitted to one or the other of two cam shafts 4 through a pinion 6 and a comparatively large gear 8, the pinion 6 being arranged to be clutched to the driving shaft 60 2 by a suitable clutch mechanism, for example, a pin clutch rendered operative by a spring 10, and moved into releasing position by the action of a wedge 12 upon a stop member 14 carried by the pin slide, said stop member 14 being arranged to coöperate with

a stop shoulder 16 upon an arm 18 of a three-armed lever fulcrumed at 20 between brackets 22 formed upon the frame 3. The stop member 16 only goes into operation in the event that the shaft 2 continues to rotate after the clutch has been rendered inoperative by the action of the wedge 12 upon the stop member 14. A second arm 24 of the three-armed lever is connected by a link 26 to a treadle 28 fulcrumed at 30 in the base of the machine, whereby the clutching of the gears 6, 8 to the power driven shaft 2 may be controlled by the operator. To prevent the unclutching of the parts before the stretching mechanism has completely performed its stretching function, a cam 32 is

provided upon each of the cam shafts 4, the cam 32 acting upon one arm 34 of a bell crank, the other arm 36 of which is connected by a link 38 to the third arm 40 of the three-armed lever, the cam 32 being so shaped that when the wedge 12 has been turned into clutch actuating position it will be maintained in this position until the shaft 4 has made such a part of its rotation

70 that the stretching mechanism has completed its stretching operation. The stretching mechanisms are operated from cams upon the shafts 4, and each mechanism comprises a standard 42, of substantially boot-leg shape, open at its side remote from the operator and provided with a base 44 bolted to a table 46 formed upon the frame 3, and a forepart form which extends away from the operator, the heel form 48 being integral

80 with the standard 42. The forepart form comprises two members 50 and 52 pivotally connected at their forward ends by means of a substantially vertical pivot stud 54 carried by a slide 56 by which the two members

90 50 and 52 may be moved together toward or away from the heel form 48. The members 50 and 52 are arranged to swing toward and away from each other about the pivot stud 54, and means is provided whereby their

95 movement to effect an extension of the forepart form is simultaneous with their movement away from the heel form. The illustrated means comprises cam slides 58 and 60 formed in a stationary supporting and guiding arm 62 carried by the standard 42 and connected to the heel form part of said standard. The guiding and supporting arm 62 is received in grooves 64 and 66 in the respective members 50 and 52, whereby these

100 members are guided both in their longitudinal and in their lateral movements, and pins 68 and 70 upon the under sides of the members 50 and 52 depend into the cam slots 58 and 60, said slots being so shaped that as the

105 slide 56 carries the forepart form away from the heel form the members 50 and 52 move away from each other about the pivot stud 54.

110 Means is provided for effecting the move-

115

120

125

130

135

140

ments of the slide through which the longitudinal and lateral movements of the members 50 and 52 are produced, the illustrated means comprising a bell crank fulcrumed at 72 in the heel form 48 and having one arm 74 received between slotted depending ears 76 upon the end of the slide 56 which extends within the heel form, trunnions 78 (see Fig. 3) upon said arm 74 being received in the slots in the ears 76. The other arm 80 of the bell crank is connected by a link 82 to a lever 84 between the fulcrum 86 of said lever and the point where said lever is acted upon by a cam 88 formed as a cam groove in a cam disk 90, the lever 84 carrying a cam roll 92 which travels in said cam groove. The lever 84 is fulcrumed upon the lug 94 formed upon a slide 96 arranged to slide in vertical guides 98 in the front of the machine, whereby the fulcrum end of the lever 84 may be raised or lowered. The initial position of the forepart form with relation to the heel form may be adjusted before the mechanism for automatically effecting relative movement of these forms is actuated. By this adjustment the stretching mechanism may be adjusted to different sizes of shoes, and the shoe may be brought into substantially taut condition before the stretching operation begins. There is one slide 96 for each pair of stretching mechanisms, whereby simultaneous and equal adjustments of the two mechanisms of either pair is effected by a movement of its slide 96 in either direction. This is important, in combination with the positive and equal stretching movements of the two mechanisms of each pair; in making the two shoes of a pair of equal size.

The raising and lowering of the slide 96 is effected in the illustrated machine by connections to a hand lever 100 located for convenient manipulation by the operator, said lever being fulcrumed at 102 upon the bracket clamp upon the table 46, and being connected by a link 104 with the slide 96. To secure the slide in its different positions of adjustment the lever 100 is provided with a locking pin 106 arranged to enter any one of a series of holes 108 arranged along the path of travel of the pin 106, the pin being spring pressed toward locking position, and being arranged to be withdrawn by means of a finger lever 110 fulcrumed upon the end of the lever 100. To facilitate the proper adjustment of the stretching mechanism to different sizes of shoes, through the raising and lowering of the slide 96, a series of indications 111 is preferably provided for the holes 108, whereby the operator, by setting the lever 100 so that the locking pin 106 will enter a hole 108 which has adjacent to it an indication corresponding to the size indication or, perhaps, some code mark upon the shoe to be stretched, may effect the proper

adjustment of the machine for a shoe of that size.

To insure the proper location of the heel end of the shoe upon the heel form and to prevent its being drawn over said form or out of position during the stretching operation, means is provided for holding the heel end of the shoe down upon the upper face of the heel form, said means also preferably comprising means for pressing the rear end of the heel up against the heel form. The illustrated heel locating or hold-down mechanism comprises a member having a part 112 arranged to engage the bottom face of the heel end of the sole of the shoe to be stretched, and to press said sole down upon the upper face of the heel form, said part being preferably so shaped that it tends to mold the shoe to the form; and another part 114 carrying a protecting pad 116 where- 85 by it may engage and press the rear end of the heel of the shoe against the heel form, or may serve simply to locate the part 112 in proper position over the bottom of the shoe. The hold-down member has depending ears 90 118 rigidly connected to arms 120 which are connected together at their lower ends by means of a rock shaft 122, Fig. 3, extending through slots 124 in the standards 42 whereby said rock shaft has provision for 95 limited vertical movement with the hold-down members. A spring 126, Fig. 2, keeps said rock shaft normally at the upper limit of its movement. The downward movement of said rock shaft whereby said hold-down 100 member is brought into engagement with the bottom of the sole, is effected automatically through connections to a cam groove 128 formed in the face of the cam 90 opposite to that in which the groove 88 is formed, said 105 connections comprising an adjustable link 130, connected to one arm of a bell crank 132, the other arm of which carries a cam roll 134 received in the cam groove 128.

It will be noted upon inspection of the 110 drawings that the hold-down member has a further important function when the machine is operating upon shoes of the type herein shown, which have out-turned flanges 115 at their heel ends. These out-turned flanges are stitched down upon the insole before the shoe is placed upon the form of the stretching machine, and if the stitching is at or inside the flange line difficulty is sometimes experienced in drawing the upper down 120 upon the heel form. The contour of the stitching in such cases being somewhat smaller than the contour of the heel seat face of the heel form there is a tendency of the insole to assume a concave shape when the 125 heel end of the upper is forced down upon the heel form. To counteract this tendency and to force the heel seat end of the insole into its proper shape the hold-down is concaved in the opposite direction so that it 130

tends to turn the projecting edges of the insole and the out-turned flange of the upper down over the sides of the heel form. It will thus be seen that the hold-down 5 stores the heel seat end of the insole of the shoe to its proper shape at the same time that it is forcing the shoe down upon the heel form so that it will not be drawn forward during the stretching operation.

10 The operation of the machine is as follows:

The parts being in the position shown in Fig. 1 and the treadle 28 being maintained in its elevated position by a spring 29, the 15 operator places a shoe upon each of the pair of forms of the stretching mechanism upon one side of the machine, moves the hold-down into position to bring the part 112 over the bottom of the sole, and the pad 116 20 against the rear face as shown in Fig. 5 of the drawings, and then grasps the handle 100, presses the finger lever 110 toward the handle 100, and lowers the slide 96 until the forepart form has entered well into the 25 toe end of the shoe, and has drawn the rear end of the shoe tight up against the heel form, or if the machine is to be adjusted with reference to definite sizes the operator will lower the slide until the handle 100 is 30 in such position that the pin 106 will enter a hole 108 having adjacent thereto an indication corresponding to some mark upon the shoe or which the operator knows will set the machine for a shoe of the size and kind 35 to be operated upon. He then depresses the treadle, thereby clutching the pinion 6 to the shaft 2 and thus causing the cam shaft 4 to rotate.

As soon as he has caused the pinion 6 to 40 be clutched to the shaft 2 he releases the treadle and the shaft 4 will be rotated substantially half a rotation or until the cam 32 permits the bell crank 34, 36, which controls the position of the wedge 12, to release 45 the wedge, which, under the action of the spring 29, will again come into its clutch releasing position. This leaves the stretching mechanism in its expanded condition, and the operator will ordinarily leave the 50 shoes upon this side of the machine upon the stretching mechanism while he is placing a pair of shoes upon the stretching forms on the other side of the machine. When he has placed the pair of shoes upon the forms 55 upon the other side of the machine he will ordinarily depress the treadle upon that side of the machine to actuate the mechanism to stretch the second pair of shoes, and will immediately thereafter depress the treadle 60 on the side of the machine upon which the first pair of shoes has been placed, to cause the stretching mechanism to move into its collapsed condition, thus permitting him to remove the shoes, and place another pair 65 of shoes upon this side while the second pair

of shoes is being allowed to set to its stretched shape on the other side of the machine.

Having described my invention, what I claim as new and desire to secure by Letters 70 Patent of the United States is:—

1. In a machine of the class described, means for stretching a shoe to a larger size, and means for adjusting said stretching means to the size of the shoe to be stretched 75 before the actuation of said stretching means.

2. Shoe stretching means constructed and arranged to be initially adjusted to the size of the shoe and to expand from said adjustment to stretch the shoe, and means for operating said stretching means a predetermined amount.

3. In a machine of the class described, means for stretching a shoe having a uniform amount of stretching movement, and means for adjusting said stretching means for the size to which the shoe is to be stretched before the actuation of said stretching means.

4. A shoe stretching machine comprising stretching means having a determined amount of stretching movement, means for effecting an initial adjustment of said stretching means for the size to which the 95 shoe is to be stretched, and power operated means for operating said stretching means to stretch the shoe to the predetermined larger size.

5. A machine for stretching and shaping 100 a shoe comprising an expandable shoe form, means for expanding said form to fill the shoe, and power operated means for expanding said form a predetermined amount after said initial expansion.

6. In a machine of the class described, means for stretching a shoe, means for operating said means by power to a predetermined extent, and means for initially adjusting said stretching means to a variable 110 point having fixed relation to the limit of the predetermined stretching movement.

7. In a machine of the class described, shoe stretching means, means for operating said stretching means, and means operating 115 through the connections between said stretching means and its operating means for effecting an initial adjustment of said stretching means to suit it to the size of the shoe to be stretched.

8. In a machine of the class described, shoe stretching means constructed to stretch the shoe both longitudinally and laterally, means for imparting to said stretching means a uniform amount of stretching movement, and means for effecting both a longitudinal and a lateral adjustment of said stretching means to the shoe to be stretched before the actuation of said stretching means.

90

105

110

115

120

125

130

9. In a machine of the class described, means for stretching a shoe and means arranged to operate the stretching means and automatically to stop the stretching means 5 when the predetermined amount of stretching movement has been reached. 70
10. Shoe stretching means constructed and arranged to be initially adjusted to the size of the shoe and to expand from said adjustment to stretch the shoe, means for operating said stretching means, and means operating automatically to stop the operation of said stretching means at the end of the stretching movement. 75
11. A machine for stretching and shaping a shoe comprising an expansible shoe form, means for expanding said form to fill the shoe, and means for automatically expanding said form a predetermined amount after 15 said initial expansion, said means being constructed and arranged to stop with the parts in expanded condition to allow the shoe to set to its stretched shape. 80
12. In a machine of the class described, a heel form and a forepart form arranged to be moved relatively toward and away from each other to effect a stretching operation, power operated means for effecting such relative movement, and manually controlled 20 means for effecting an initial relative movement of adjustment after the shoe to be stretched has been placed upon said forms. 85
13. In a machine of the class described, the combination with a stationary heel form 25 and a forepart form arranged to move toward and away from said heel form, of power operated means for effecting such movement of the forepart form, and manually controlled means for effecting an initial adjustment of said forepart form after 30 the shoe to be operated upon has been placed on said forms. 90
14. In a machine of the class described, the combination of the heel form and the 35 expansible forepart form, said heel and forepart forms being relatively movable to effect the stretching operation, means for effecting such relative movement of said forms and simultaneously expanding said 40 forepart form, and manually controlled means for effecting an initial adjustment of said forms with respect both to the relative longitudinal movement and to the expanding movement of said forepart form, 45 after the shoe has been placed upon said forms. 100
15. In a machine of the class described, a heel form and a forepart form arranged for a movement of separation to stretch the 50 shoe, means for operating said forms to effect such movement, and manually controlled means operating through elements of said operating means to effect an initial separation of said forms, said means being 55 so constructed and arranged as to vary the 105
- initial relative position of said forms without varying substantially the amount of separating movement imparted to said forms during the operation of said operating means. 70
16. In a machine of the class described, a heel form and a forepart form arranged to have relative movements of approach and separation whereby a shoe may be located upon said forms and stretched, means for effecting such movements comprising a cam and a lever having an adjustable fulcrum, and means for adjusting the fulcrum of said lever to effect an initial relative movement of said forms before the relative stretching 75 movement is effected. 80
17. A machine of the class described, comprising, in combination, a heel form and a forepart form arranged for movement of separation to effect the longitudinal stretching of a shoe, and means for holding the heel end of the shoe down upon said heel form during said stretching operation. 85
18. A machine of the class described, comprising, in combination, a heel form and a forepart form arranged for a movement of separation to effect the longitudinal stretching of the shoe, means for effecting such movement of separation, and means operating automatically to hold said shoe 90 down upon said heel form during the stretching operation. 95
19. In a machine of the class described, a heel form and a forepart form arranged for relative movement of separation to effect the longitudinal stretching of a shoe, and means for holding the heel end of the shoe down upon said heel form, constructed to mold the heel end of the sole to the proper shape. 100
20. In a machine of the class described, a pair of stretching mechanisms constructed and arranged to receive a pair of shoes to be stretched, means for operating said mechanisms to stretch the pair of shoes, and means arranged to effect simultaneously equal adjustments of said stretching mechanisms to the size of the pair of shoes 110 before the stretching operation. 105
21. In a machine of the class described, a pair of stretching mechanisms constructed and arranged to receive a pair of shoes to be stretched and to be initially adjusted to the size of said pair of shoes, and means operating to effect simultaneously equal stretching 115 movements of said stretching means. 120
22. In a machine of the class described, a pair of stretching mechanisms constructed and arranged to receive a pair of shoes to be stretched, means for causing said stretching mechanisms to effect stretching operations equal in extent, and a single means for effecting equal initial adjustments of said mechanisms to the size of the pair of shoes. 125
23. In a machine of the class described, a 130

- pair of stretching mechanisms, means for causing said stretching mechanisms to effect positive stretching movements equal in extent, and a single means through which 5 equal initial adjustments of said mechanisms to the size of the pair of shoes may be effected.
24. In a machine of the class described, shoe stretching means constructed and arranged to be initially adjusted to the size of the shoe, combined with power driven means for operating the stretching means to stretch the shoe longitudinally and to stretch the shoe at the same time laterally from the ball 10 portion toward the toe.
25. In a machine of the class described, shoe stretching means constructed and arranged to be initially adjusted to the size of the shoe, combined with power driven 15 means for operating the stretching means to stretch the shoe longitudinally and to stretch the shoe laterally by progressively lessening amounts from the ball portion toward the toe.
26. In a machine of the class described, shoe stretching means constructed and arranged to be initially adjusted to the size of the shoe, combined with power driven means for operating the stretching means to stretch 20 the shoe laterally by progressively lessening amounts from the ball portion toward the toe.
27. In a machine of the class described, shoe stretching means constructed and arranged to be initially adjusted to the size of the shoe, means for operating the stretching means to stretch the shoe longitudinally and laterally, the lateral stretching bearing a fixed ratio to the longitudinal stretching.
28. In a machine of the class described, shoe stretching means constructed and arranged to be initially adjusted to the size of the shoe, means for operating the stretching 30 means to stretch the shoe longitudinally and laterally, the longitudinal stretching being of predetermined amount and bearing a fixed ratio to the lateral stretching.
29. A shoe stretching machine having, in combination, shoe stretching means constructed and arranged to stretch the shoe longitudinally and laterally, manual means for setting the stretching means to fill the shoe longitudinally and to fill it laterally across the ball, and means for effecting a further longitudinal movement of the stretching means and a further movement to stretch the shoe laterally across the ball and forepart only.
30. A machine for use in the manufacture 40 of shoes having, in combination, a tool for operating upon the shoe, manually operated means to set the tool for a particular operation upon the shoe, and automatic means to actuate the tool a further predetermined 45 distance in the direction of said adjustment to perform the intended operation upon the shoe and then come to rest.
31. A shoe stretching machine having, in combination, a member constructed and arranged for elongation to stretch the shoe, 50 manual means for effecting a preliminary elongation which may be determined by the particular shoe being operated upon, and automatic means to effect a further elongation of predetermined amount and then 55 come to rest with the member in elongated condition.
32. A shoe stretching machine having, in combination, a member constructed and arranged for elongation to stretch the shoe, 60 manual means for effecting a preliminary elongation which may be determined by the particular shoe being treated, and automatic means for effecting a further elongation of predetermined amount independently of the extent of the manual elongation.
33. A shoe stretching machine having, in combination, a heel form, a forepart form movable relatively to the heel form to 65 stretch the shoe longitudinally and comprising laterally separable members pivotally connected near their front ends, inclined guideways on the heel form and guide studs on the rear ends of said members arranged 70 by action of the guideways thereon to separate the rear ends of said members proportionally to the longitudinal stretching movement of the heel form and forepart form relatively.
34. A machine of the class described having, in combination, an expansible last for a shoe, and automatic mechanism to give the last a predetermined degree of positive expansion and then come to rest with the 75 last in expanded position to hold the shoe stretched.
35. A machine of the class described having, in combination, an expansible last for a shoe, and automatic mechanism under the 80 control of the operator for distending the last to a predetermined size and then coming to rest with the shoe distended.
36. A machine of the class described having, in combination, an expansible last for a shoe, manual means for setting the last in accordance with the initial size of the shoe being treated, and automatic means for giving the last a predetermined amount of expansion beginning at the initial setting and then coming to rest.
37. A machine of the class described having a heel part and a relatively movable forepart, operating means connected with the forepart to move it to distend the shoe, 100 and means positively limiting the extent to which such distention shall be effected.
38. In a machine of the class described, the combination of an expansible last having a heel part and a relatively movable 105

forepart, power driven means for operating the forepart to distend a shoe, and mechanism constructed and arranged to cause the shoe distending movements to cease after the shoe has been distended a predetermined amount and to then disconnect the power driven means from the source of power.

39. A machine of the class described having, in combination, an expansible last having, a heel part and a relatively movable forepart, means for automatically moving the two parts relatively a predetermined amount to expand the last, and manual means for effecting an initial adjustment of the forepart and heel part for shoes of different sizes without thereby affecting the length of expanding movement of the last.

40. In a machine of the class described, shoe stretching means comprising a slide movable endwise of a shoe, a forepart member divided longitudinally of the shoe and pivoted to the slide at one end, means for moving the slide and forepart member lengthwise, and means for effecting separa-

tion of the rear ends of the forepart member by movement of the slide toward the toe.

41. In a machine of the class described, means for stretching a shoe, means for adjusting the stretching means to the size of the shoe to be stretched, and means for thereafter so actuating the stretching means as to stretch the shoe and automatically to stop the stretching movement at a predetermined point.

42. In a machine of the class described, power driven means for stretching a shoe to a predetermined extent, and automatic means for controlling the extent of the stretching movement.

In testimony whereof I have signed my name to this specification in the presence of two subscribing witnesses.

MATTHIAS BROCK.
